US0D1058048S

(12) **United States Design Patent** (10) **Patent No.:** **US D1,058,048 S**
(45) **Date of Patent:** **** Jan. 14, 2025**

(54) **EYELASH EXTENSION**

(71) Applicant: **Qingdao Jiahe Yongrun Beauty Technology Co., Ltd.**, Qingdao (CN)

(72) Inventor: **Yaxing Jiang**, Qingdao (CN)

(73) Assignee: **Qingdao Jiahe Yongrun Beauty Technology Co., Ltd.**, Qingdao (CN)

(**) Term: **15 Years**

(21) Appl. No.: **29/964,374**

(22) Filed: **Sep. 23, 2024**

(51) LOC (15) Cl. **28-03**

(52) U.S. Cl.

USPC **D28/92**

(58) **Field of Classification Search**

USPC **D28/92, 93, 99**

CPC **A41G 5/02**

See application file for complete search history.

(57) **CLAIM**

The ornamental design for an eyelash extension, as shown and described.

DESCRIPTION

FIG. 1 is a perspective view of an eyelash extension embodying the new design;

FIG. 2 is another perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings show portions of the eyelash extension that form no part of the claimed design.

1 Claim, 8 Drawing Sheets
